UNITED STATES PATENT OFFICE.

GEORGE E. WHITNEY, OF BRIDGEPORT, CONNECTICUT, ASSIGNOR TO INTERNATIONAL PAVEMENT COMPANY, OF HARTFORD, CONNECTICUT, A CORPORATION OF CONNECTICUT.

PRESS.

1,317,115.

Specification of Letters Patent. Patented Sept. 23, 1919.

Application filed December 4, 1916. Serial No. 134,891.

To all whom it may concern:

Be it known that I, GEORGE E. WHITNEY, a citizen of the United States, and a resident of Bridgeport, in the county of Fairfield and State of Connecticut, have invented an Improvement in Presses, of which the following description, in connection with the accompanying drawings, is a specification, like characters on the drawings representing like parts.

This invention pertains to an improvement in presses and more particularly to improvements in molding presses of the rotary mold type. One of the principal difficulties attending the operation of said presses is to produce uniform intermittent partial unidirectional rotation of the revolving mold carrying table or head. The principal obstacles to be overcome are the intermittent engagement of the rotary mold table by the mold table operating means and to secure accurate stoppage of the mold table during its periods of rest, so that the mold table may register accurately with the mold filling means, under which the plurality of molds carried by the mold table are usually successively brought in register.

It is among the objects of my invention to solve the difficulties above referred to and to this end I provide certain novel mechanisms which are typified by one embodiment of a preferred construction of my invention, as shown in the drawings.

As the present invention relates more particularly, but not exclusively, to mold table operating mechanism, I have elected to disclose my invention in connection with a type of press shown and described in Patent No. 1,174,212, issued March 7, 1916.

40 Referring to the drawings, which show one illustrative embodiment of a preferred construction of my invention,

Figure 1 is a side elevation thereof;

Fig. 2 is a plan view thereof;

45 Fig. 3 is a sectional elevation thereof, taken on the line 3-3 of Fig. 2;

Fig. 4 is a section partially broken away on the line 4-4 of Fig. 2; and

50 Fig. 5 shows a detail of the valve operating mechanism, which will be hereinafter described.

Referring to Fig. 2, I have shown a bed plate 10 carrying a pressure fluid cylinder 11 having a piston therein connected by a piston rod 12 to a displacing plunger 13

adapted to displace liquid in a cylinder 14, thereby to impart compressive movement to a ram 15 in the same general manner, as shown in my earlier Patent No. 1,174,212.

Mounted on the bedplate 10, I preferably provide a single cycle timing shaft 20, which may be and preferably is driven by a gearing 21-22 from a driving shaft 23, to which power may be imparted by a pulley 24 driven from any suitable source of power.

The pressure system and power system, before described, form no part of the present invention and are not herein illustrated nor described.

Rising from bed plate 10, I preferably provide a mold carrier supporting column 30, on which is rotatably mounted the mold carrier 31 having a plurality of molds 32. Above the mold carrier 31 I preferably provide an abutment 33 carried by the columns 30-34-35 provided with a pressure block 36 (Fig. 3) adapted to close the top of that mold which is above the ram 15. Each mold may be and preferably is provided with a mold plunger 37, each reciprocable in its mold and rotatable with said mold table 31. Above the mold table 31, I preferably provide a mold filling neck or conduit 38.

The before described instrumentalities may be and preferably are very similar to those shown in my patent previously referred to. I will now describe a preferred construction of the improved mold table operating means, which constitutes one form of constantly engaged turret moving means. I preferably provide a gear 40 concentric with, and preferably attached to, the rotatable mold table 31. Said gear 40 is preferably constantly engaged with a mold table driving pinion 41 which is keyed to a mold table driving shaft 42 adapted to receive intermittently effective rotary movement from pressure fluid actuated instrumentalities, more fully described hereafter. The mold table driving shaft 42 may extend through the pinion 41 into a bearing 43 carried by the abutment 33, and the lower end of said shaft 42 may be provided with a bearing 44 on the bed plate 10 of the press. Keyed to the shaft 42 preferably adjacent the bottom end thereof, I may and preferably do provide a worm gear 45 adapted to be driven by a worm 46 directly connected to the shaft 47 of a pressure fluid engine 48,

the valve mechanism of which will be more fully described hereafter. Through the before described train of gearing, the mold table 31 will be rotated as and when the 5 rotary movement is imparted to the crank shaft 47 of the engine 48.

The mold table operating instrumentalities, before described, must be effective to impart intermittent partial rotation to the 10 mold table 31, each partial rotation preferably being the exact distance between two adjacent molds of the mold table 31. To this end I may and preferably do make the gear 40 contain a number of teeth, equal to the 15 number of teeth in the mold table driving pinion 41, multiplied by the number of molds in the mold table. Thus one revolution of the driving pinion 41 imparts to the mold table 31 an amount of movement exactly 20 equal to the distance between two adjacent molds of the mold table.

While it is not essential for all purposes of my invention that the gear 40 bear the ratio to the pinion 41, above mentioned, it 25 is necessary that the amount of rotation imparted to the pinion 41 at each cycle of operation of the press be exactly the same. It is also essential that such movement be timed with relation to the periods of operation 30 of the compressing instrumentalities and other coöperating instrumentalities of the press. To this end I provide means on the timing shaft 20 of the press typified by the cam 50, which constitutes one form of timing means for the mold table operating 35 means.

The pressure fluid engine 48 is preferably multi-cylndered and may be as shown, provided with two cylinders 51—51^a with pistons 52—52^a, piston rods 53—53^a and connecting rods 54—54^a, engaging the cranks 47—47^a of the crank shaft 57. The cylinder 51^a is provided with a slide valve 56 having its exhaust cavity somewhat longer than is 45 the usual construction, such additional length being provided so that when the slide valve 56 is in the central position, both ends of the cylinder 51^a will be exhausted to the atmosphere. The slide valve 55 of the cylinder 51 is preferably without any substantial outside lap and the exhaust cavity is preferably of the usual proportions, so that both ends of the cylinder 51 cannot be exhausted when the valve is in central position. Each of 55 the slide valves 55 and 56 is provided with an eccentric of the usual construction on the crank shaft 57, so that when said slide valves are reciprocated by said eccentric, the pressure fluid engine will impart unidirectional 60 clockwise rotation to the turret 31.

To provide for stopping and starting the turret, I preferably provide a link connection 60 between the slide valve 56 and its eccentric and a link connection 61 between 65 the slide valve 55 and its eccentric. The

links 60 and 61 are provided with dead rods 63—63^a, the latter being adapted to hold the slide valve 56 in central position and the former to hold the slide valve 55 in its extreme lower position. The dead rods 70 63—63^a are connected to the shaft by centric connections.

Referring now to Fig. 3, I will describe the mechanism for shifting the links 60—61 to start and stop the pressure fluid engine. 75 The movement of the valve controlling links 60—61 from the position shown in Fig. 3 to the left to start the engine, is actuated by the timing cam 50 on the timing shaft 20 which rocks the lever 70, fulcrumed at 71 on the bedplate 10. Said lever 70 is connected at its upper end by a rod 72 with a lever 73, fulcrumed on a rocker shaft 74 and connected at its lower end through the connection 75 to the valve controlling link 60. 80 Similar connections between the rocker shaft 74 and the link 61 provide for shifting of the latter link in unison with the shifting of the link 60. When the links 60—61 are shifted to the left from the position shown in Fig. 3, the connection between the eccentrics and the slide valves immediately becomes operative to reciprocate the latter, thereby admitting steam to the cylinders to cause operation of the engine. 90

Conversely, when the links 60—61 are shifted to the right, the lengths of the dead rods are such that the engine is stopped or locked, because the slide valve 56 is held in central position, thereby exhausting both 100 ends of the cylinder 51^a while the slide valve 55 is held in its downward position, thereby admitting full steam pressure to the top of the cylinder 51. The links 60—61 are shifted to the right by means of a cam 105 77 on the shaft 42, said cam 77 rocking the lever 78 which engages an arm 79 on the rocker shaft 74.

The timing shaft 20 thus initiates the 110 operation of the turret moving engine 48. I preferably provide, however, means for stopping said engine, which is not dependent on movement of the timing shaft 20, but which is controlled by an element actuated by the turret moving engine and to this end 115 I have provided the lever 76 on the shaft 74, said lever 76 thereby constituting in effect an offset extension of the lever 73, said extension being adapted when operated on by a cam 77 on the turret moving shaft 42 120 through an interposed lever 78 to shift the links to the right in position to stop the engine.

Thus the valve mechanism of the pressure fluid engine 48 is shifted to operative position by means connected to the timing shaft 20 and is shifted to non-operative position by means actuated by the engine 48, the latter means being in effect controlled by the amount of movement given to the mold table 125 130

31 by the pressure fluid engine 48. It is clear that were the engine 48 both started and stopped by the timing shaft 20, the turret would not be stopped after any 5 definite amount of movement, for the number of revolutions which the pressure fluid engine 48 would make between the inertia of movement by the timing shaft 20 and the stoppage of said movement would 10 be dependent upon the steam pressure and on the resistance to rotation of the turret. By the described independent means for initiating the starting of the engine 48 and for producing stoppage thereof, the amount 15 of time during which the engine may run at each movement of the turret may vary, but the number of revolutions which it will make during such period will be constant, thereby insuring accurate positioning of the 20 turret at each stoppage thereof. It will be noted that by the foregoing arrangement I have provided turret moving means which constantly engages the turret, thereby eliminating the difficulties usually attending the 25 alternate connection and disconnection of a constantly moving turret operating element with the turret. The engine 47 will always start when the valve controlling links 60 and 61 are shifted to valve operating position because the cranks are set at 90° thereby eliminating dead center. To permit sudden stoppage of the engine, I preferably omit the usual fly wheel, thereby reducing the inertia attending the sudden 30 stopping and starting of the engine. To permit rapid operation of the press, I may provide such a ratio of gearing between the crank shaft 47 and the turret 31 as will permit rapid turning of the turret 31 without 35 increasing unduly the speed of operation of the pressure fluid engine 48.

While I have shown in the drawings and have described one specific embodiment of a preferred construction of my invention, 45 it will be understood that my invention is not limited to the embodiment shown and described, but that major changes involving omissions, substitutions, alterations and rearrangement of parts, may be made without 50 departing from the scope of my invention, which is best defined by the following claims:

Claims.

1. A molding press comprising in combination an intermittently, step by step rotatable pressure fluid actuated mold table; and pressure fluid actuated operating means constantly operatively connected to said mold table during periods of motion and 55 rest of said mold table and transmitting every movement of said operating means to said table.

2. A molding press comprising in combination an intermittently, step by step rotatable mold table; and pressure fluid actu- 60

ated operating means constantly operatively connected to said mold table during periods of motion and rest of said mold table and transmitting every movement of said operating means to said table. 70

3. In a molding press a combination of an intermittently, step by step rotatable mold table having a plurality of molds; a gear constantly operatively connected thereto, a pinion constantly meshing with said gear; and pressure fluid actuated operating means for said pinion constantly operatively connected thereto and transmitting every movement of said operating means to said table. 75

4. In a molding press a combination of an intermittently, step by step, rotatable mold table having a plurality of molds; a gear constantly operatively connected thereto; a driving means constantly engaging said gear; and pressure fluid actuated operating means for said driving means constantly operatively connected thereto and transmitting every movement of said operating means to said table. 80

5. In a molding press a combination of an intermittently, step by step rotatable mold table having a plurality of molds; a gear constantly operatively connected thereto; a pinion constantly engaging said gear; pressure fluid operating means for said pinion constantly operatively connected thereto; and automatic timing means for said operating means. 95

6. In a molding press a combination of a rotatable mold table having a plurality of molds; a gear constantly operatively connected thereto; a pinion constantly engaging said gear; operating means for said pinion constantly operatively connected thereto; timing means for said operating means including a starting element actuated by the timing shaft of said press and a stopping element actuated by said actuating means. 105

7. A molding press comprising in combination a rotatable mold table; operating means therefor permanently, operatively connected to said mold table; timing means for said operating means, including means operated by the timing shaft of said press for initiating movement of said operating means; and means actuated by said operating means for stopping movement thereof. 110

8. A molding press comprising in combination a rotatable mold table; pressure fluid actuated operating means therefor permanently, operatively connected to said mold table; timing means for said operating means, including means operated by the timing shaft of said press for initiating movement of said operating means; and means actuated by said operating means for stopping movement thereof. 115

9. A molding press comprising in combination a rotatable mold carrier having a plurality of molds; a pressure fluid engine for 120

125

effecting rotation of said mold table; gearing constantly connecting said pressure fluid engine to said mold table; and automatic timing means for timing the periods of operation and rest of said pressure fluid engine and of said mold table.

10. A molding press comprising in combination a rotatable mold carrier having a plurality of molds; a multi-cylinder pressure fluid engine for effecting rotation of said mold table; gearing constantly connecting said multi-cylinder pressure fluid engine to said mold table; and automatic timing means for timing the periods of operation and rest of said pressure fluid engine and of said mold table.

11. A molding press comprising in combination a mold table; a pressure fluid actuator therefor; gearing constantly connected 20 to said pressure fluid actuator and to said mold table during both the periods of movement and of rest of said mold table; and timing means for said pressure fluid engine, including means for shifting a valve 25 element of said engine into stopping position to stop said engine and automatic means to shift said valve into starting position to start said engine.

12. A molding press comprising in combination a mold table having a plurality of molds and intermittent mold table operating means including a pressure fluid cylinder; its piston and valve means for admitting pressure fluid to said cylinder and retaining pressure fluid against one side of said piston to prevent momentum actuated movement of said mold table at a predetermined point.

13. A press having an intermittently step 40 by step rotatable mold table; an actuator for said mold table; and constantly connected power transmitting means operatively interposed between said actuator and said mold table and transmitting every movement of said actuator to said mold table.

14. A press having an intermittently rotatable mold table; a yielding actuator therefor; a positive constantly connected train of gearing intermediate said yielding 50 actuator and said table and constantly connecting the two; and timing means for timing the periods of operation of said yielding actuator relative to the co-operating instrumentalities of said press.

15. A molding press comprising in combination a rotatable mold table and pressure fluid means for actuating intermittent partial unidirectional rotation of said mold table and for holding said mold table stationary in a predetermined position, said pressure fluid means starting and stopping for every movement of said mold table.

16. A molding press comprising in combination a rotatable mold table; a multi-

cylinder engine for effecting rotation of said mold table; a pressure fluid controlling valve for one cylinder of said engine; means for operating said valve during operation of said engine; and means for shifting said valve to stop said engine.

17. A molding press comprising in combination a rotatable mold table; a multi-cylinder engine for effecting rotation of said mold table; a pressure fluid controlling valve for one cylinder of said engine; means for operating said valve during operation of said engine; and link means for shifting said valve to stop said engine.

18. A molding press comprising in combination a rotatable mold table; a multi-cylinder engine for effecting rotation of said mold table; a pressure fluid controlling valve for one cylinder of said engine; means for operating said valve during operation of said engine and a link connection between 85 said means for operating said valve and said valve providing one position for operating the engine and another position for locking said engine after a predetermined number of revolutions.

19. A molding press comprising in combination a rotatable mold table and a pressure fluid engine for effecting intermittent rotation of said mold table; said pressure fluid engine being provided with valve mechanism and link mechanism controlling said valve mechanism, including a link having one end connected to an eccentric connection and the other end connected to a centric connection.

20. A molding press comprising in combination a rotatable mold table and a pressure fluid engine for effecting intermittent rotation of said mold table; said pressure fluid engine being provided with valve mechanism and link mechanism controlling said valve mechanism, including a link having one end connected to an eccentric connection to operate the engine and the other end connected to a centric connection to stop 110 the engine.

21. A molding press comprising in combination a rotatable mold table and a pressure fluid engine for effecting intermittent rotation of said mold table; said pressure fluid engine being provided with valve mechanism and link mechanism controlling said valve mechanism, including a link having one end connected to an eccentric connection to operate the engine and the other end connected to a centric connection to stop 115 the engine after a predetermined number of revolutions thereof.

22. A molding press comprising, in combination, an intermittently rotatable mold table; pressure fluid actuating means for imparting step-by-step rotation to said table and constantly connected thereto; and auto-

matic timing means for starting and stopping said pressure fluid actuating means and to start and stop said table.

28. A molding press comprising, in combination, a rotatable mold table; pressure fluid means for effecting step-by-step, intermittent, unidirectional rotation of said mold table and for opposing momentum-actuated excess movement of said mold table.

10 24. A molding press comprising, in com-

bination, a rotatable mold table; a plurality of pressure fluid cylinders for effecting intermittent, unidirectional, partial rotation of said mold table; valve mechanisms for said cylinders and valve shifting means actuated by the timing shaft of said press.

In testimony whereof, I have signed my name to this specification.

GEORGE E. WHITNEY.

Copies of this patent may be obtained for five cents each, by addressing the "Commissioner of Patents, Washington, D. C."

It is hereby certified that in Letters Patent No. 1,317,115, granted September 23, 1919, upon the application of George E. Whitney, of Bridgeport, Connecticut, for an improvement in "Presses," an error appears in the printed specification requiring correction as follows: Page 5, line 2, claim 22, for the word "and" read *thereby*; and that the said Letters Patent should be read with this correction therein that the same may conform to the record of the case in the Patent Office.

Signed and sealed this 21st day of October, A. D., 1919.

[SEAL.]

M. H. COULSTON,
Acting Commissioner of Patents.
